UNITED STATES PATENT OFFICE.

JOHN J. KNOX, OF LOS ANGELES, CALIFORNIA.

SHINGLING-GAGE.

SPECIFICATION forming part of Letters Patent No. 772,521, dated October 18, 1904.

Application filed February 8, 1904. Serial No. 192,707. (No model.)

To all whom it may concern:

Be it known that I, JOHN J. KNOX, a citizen of the United States, residing at Los Angeles, in the county of Los Angeles and State of California, have invented new and useful Improvements in Shingling-Gages, of which the following is a specification.

My invention relates to a gage to determine the correct position of the courses of shingles 10 as they are being laid upon a roof or upon the walls of the buildings; and the object thereof is to provide a simple and efficient gage that will accurately determine the position of the course to be laid and which can be quickly adjusted for a new course. I accomplish this 15 object by the gage described herein and illustrated in the accompanying drawings, in which—

Figure 1 is a perspective view of a fragment 20 of the roof and a perspective view of my improved shingling-gage in place thereon. Fig. 2 is a fragment of my gage to show its method of construction when the same is extensible.

In the drawings, A represents the shingles 25 on the roof, of which there are three courses (illustrated as A, A', and A'') and a part of a fourth course. Resting partly upon the course A' and A'' is my improved shingling-gage, which gives the correct position of the placing 30 of the course being put on. This gage consists of two parallel gage-bars B, which when not made adjustable are preferably formed of wood, oak or ash being preferred. The ends of these bars are connected together 35 by adjustable link-bars C to enable the bars to be adjusted for use on roofs where the shingles are laid at different distances to the weather. These link-bars are made in two sections, one of which is provided with a slot 40 C', through which screw-bolts D project, the other ends of the screw-bolts passing through holes in the other section of the link-bar and being provided with nuts E, so that after the 45 sections of the links are adjusted to hold the gage-bars at the required distance apart the nuts may be tightened on the bolts to prevent the sections of the link-bars from sliding. The ends of these link-bars are pivotally secured to the gage-bars by pivots F, so that 50 when shingling the lower gage-bar may be

lifted by its handle B' and placed over the other gage-bar upon the roof to form a gage for the next course of shingles. On the lower side of the gage-bars are attaching-hooks G, which are pivotally mounted to bearings H, 55 secured to the gage-bars. These hooks I term "horizontal" attaching-hooks, because when in use they lie in the same plane that the gage-bars lie in. These attaching-hooks pass through release-hooks I, also secured to the 60 gage-bars. One of the gage-bars is preferably provided with a bubble-glass J, by means of which the operator is enabled to run a straight line of shingles without using a chalk-line and to instantly detect any variation in 65 his shingle-course from a line perfectly parallel with his first-course line of shingles.

Where the gage is intended for use in shingling vertical walls, I provide additional or vertical attaching-hooks K, which are mounted in slots L, which extend vertically through the gage-bars. By "vertical" as applied to 70 these hooks and slots I mean that they are at right angles or vertical to the plane in which the gage-bars lie when in use.

In practice I have found that a shingling-gage in which the gage-bars are two feet and one-half long produces a very satisfactory tool; but where it is desired to have a longer gage I preferably construct a case M of sheet- 80 steel and provide a telescoping member N, having a slot M' therein of wood. This telescoping member, however, may be made of metal if desired. The link-bars are pivotally secured to the telescoping member, and I prefer to have the attaching-hooks secured to the top of the case, as shown. A bolt O is secured to the lower side of the case and passes through the slot in the telescoping member and through the upper side and is provided 85 with a wing-nut P, by means of which the case may be clamped to hold the telescoping member firmly in place.

In the use of my shingling-gage the first row or eaves-row of shingles are laid in the usual 95 manner. The gage-bars are spaced apart so that from the inner edge of one gage-bar to the outer edge of the other gage-bar equals the distance that it is intended to lay the shingles to the weather. The inner edge of 100

the lower gage-bar is then brought up against the butts of the first row of shingles and the attaching-hooks of the upper bar are then driven into the shingles, which securely holds 5 the gage in place on the roof. The shingler then lays the butts of the shingles of the next row against the upper gage-bar and nails them in place. As soon as he has laid as many shingles as the length of his gage he catches 10 the lower gage-bar by the handle and places it on the roof above the other gage-bar and drives one or both of the attaching-hooks into the shingles, and then lays another row of shingles the length of the gage. He then 15 moves the lower gage-bar up over the other and repeats the operation. After the roof is well started the attaching-hooks of the lower gage-bar are released from engagement with the shingles by striking the handle on the 20 lower side thereof a slight blow with the shingling-hammer, thereby causing the rotation of the gage-bar slightly and causing the release-hooks to raise the attaching-hooks out of engagement with the shingles. Shingling 25 vertical walls both sets of attaching-hooks are used. In this case the vertical attaching-hooks are released by striking them upon the end which projects above the gage-bar.

It will thus be seen that I have provided a 30 simple and efficient shingling-gage by the use of which a workman can lay a great many more shingles in a given time than if he had to lay them by chalk-line or by the use of a gage attached to his shingling - hatchet, as 35 the lower bar is always securely held in place while the upper bar is shifted to place, and that the links always cause the upper bar to reach the proper place for the next row of shingles.

40 Having described my invention, what I claim as new, and desire to secure by Letters Patent, is—

1. A shingling-gage composed of two parallel gage-bars united at their ends by link-bars pivotally connected to said gage-bars at 45 the ends thereof by pivots lying in the longitudinal axes of said bars, said links being adapted to turn in a plane at right angles to the longitudinal axes of said gage-bars, said

gage-bars having means to attach them to the 50 shingles of the roof.

2. A shingling-gage comprising two bars; links pivotally connected to said bars at the ends thereof and adapted to turn in a plane at right angles to the longitudinal axes of said 55 gage-bars, said links being composed of sections adjustably connected to each other; and means to attach said gage to the shingles.

3. A shingling-gage comprising two bars; link-bars pivotally connected to the said bars at 60 the ends thereof, said link-bars being composed of sections adjustably connected to each other; attaching-hooks and handles secured to said gage-bars.

4. A shingling-gage comprising two gage-bars; links pivotally connected to said bars at the ends thereof, said links being composed of sections adjustably connected to each other; handles secured to said gage-bars near the center thereof; two attaching-hooks pivotally 70 connected to each of said gage-bars near the ends thereof; a bubble-glass secured to one of the said gage-bars.

5. A shingling-gage comprising two gage-bars; link-bars pivotally connected to said 75 gage-bars at the ends thereof and composed of sections adjustably connected to each other; handles secured to said gage-bars at the center thereof; two sets of attaching-hooks secured to said gage-bars, one set of hooks being mounted in a plane which lies at right angles to the plane in which the other set of hooks are mounted.

6. A shingling-gage comprising two gage-bars provided with extensible sections at each 85 end thereof; link-bars pivotally connected to the said extensible ends, said link-bars being composed of sections adjustably connected to each other; handles secured to said gage-bars near the center thereof; attaching-hooks secured to said gage-bars.

In witness that I claim the foregoing I have hereunto subscribed my name this 2d day of February, 1904.

J. J. KNOX.
